UNITED STATES PATENT OFFICE.

DANIEL M. SWEENEY, OF SAN FRANCISCO, CALIFORNIA.

SPARK-GAP MECHANISM.

1,173,324.

Specification of Letters Patent. Patented Feb. 29, 1916.

Application filed July 19, 1915. Serial No. 40,753.

To all whom it may concern:

Be it known that I, DANIEL M. SWEENEY, a citizen of the United States, residing at San Francisco, in the county of San Francisco and State of California, (whose post-office address is 507 Brannan street, San Francisco, California,) have invented a new and useful Spark-Gap Mechanism, of which the following is a specification.

10 My invention relates to improvements in spark-gap mechanisms in which electrical contact is completed through a conducting arm or support removably attached at one end to an igniting mechanism and attached at the other end at right angles to a tube or chamber comprising the spark-gap of a high-tension electric circuit.

My invention is illustrated in the accompanying drawing, in which—

20 Figure 1 is a vertical section of the entire mechanism; Fig. 2, a top view, and Fig. 3, a side view in perspective showing its attachment to an igniting mechanism or "spark plug".

25 Similar letters refer to similar parts throughout the several views.

A represents a vertical central screw of metal or other suitable conducting material pointed at the lower end.

30 D is an insulating nut into which A is threaded.

C is a lock-nut for securing A and preventing it from turning in D.

35 B is a clamping nut, preferably milled on its upper edge, for clamping a conducting wire, H, Fig. 3, in contact with C.

E represents a hollow cylindrical chamber, into which the upper end of the insulating nut, D is screwed. To the lower closed end of E, and extending from it substantially at right angles to its axis, is attached the conducting arm, F, having a perforation, G. At the center of the bottom of E is an internal upwardly projecting point, L, through which the electric spark passes to the point of the screw, A.

The entire mechanism is attached to the fixed "spark plug", K, by means of the screw, I, and nut, J.

What I claim as my invention and desire to secure by Letters Patent of the United States is—

1. In a spark mechanism a vertical conducting screw, adjustably secured in an insulating nut and pointed at the inner end, in combination with a conducting cylindrical chamber and a conducting arm substantially at right angles to the axis of said chamber, substantially as herein set forth.

2. In a spark mechanism a vertical conducting screw adjustably secured in an insulating nut co-axially with a conducting cylindrical chamber, the screw and bottom of the chamber being provided with points for the transmission of an electric discharge, substantially as set forth.

DANIEL M. SWEENEY.
